PAPER RULING MACHINE

Louis S. Forsythe, Portsmouth, Va.

Application October 5, 1936, Serial No. 104,137

1 Claim. (Cl. 33—45)

This invention relates to ruling machines for paper or the like and more particularly to the method of supporting and adjusting the pens of such machines.

An important object of the present invention is the provision of a ruling machine provided with an adjusting mechanism which may be readily operated to adjust the spacing of the pens.

A further object of my invention is to provide a device of this character which will always maintain the even spacing and parallel arrangement of the pens.

Still another object of my invention is the provision of a device of this character which is of simple and inexpensive construction, which may be built into a new machine or made as an attachment to be placed on machines in use, and which is of positive and simple operation.

Other objects and advantages of my invention will be apparent during the course of the following description.

In the accompanying drawing which forms a part of this specification and wherein like characters of reference denote like parts throughout, Figure 1 is a side elevation of a portion of a ruling machine embodying my invention,

Figure 2 is a top plan view thereof,

Figure 3 is a transverse sectional view through the machine on the line 3—3 of Figure 2,

Figure 4 is a similar view on the line 4—4 of Figure 2,

Figure 5 is a longitudinal sectional view on the line 5—5 of Figure 2,

Figure 6 is an enlarged fragmentary sectional view through one end of the adjusting mechanism, and,

Figure 7 is a longitudinal section taken on line 7—7 of Figure 2.

In the drawing, wherein for the purpose of illustration is shown a preferred embodiment of the invention the numeral 10 designates the side rails of the frame of the machine between which the flexible belt 11 of fabric or the like moves to convey the sheets of paper past the pens. Upright standards 12 are bolted to the top of each rail 10 at diametrically opposite points to support the pen carrying mechanism. One side of each standard is provided with a flat leaf spring 13 bolted to the standard at a point spaced a substantial distance below the top thereof, the springs 13 extending a substantial distance above the tops of the standards. Elongated bearing members or blocks 14 are spaced a slight distance above the standards 12 and secured at their ends by bolting or the like to the flat leaf springs

13. The bearing blocks 14 extend longitudinally of the rails 10 above the tops of standards 12 and spaced therefrom, being normally held in a substantially horizontal position by the tension of springs 13 but being capable of movement against the tension of the springs 13.

A pair of guide shafts 15 are received in horizontal transverse bores arranged adjacent the ends of the bearing blocks 14 and are secured against rotation in the blocks 14 by means of set screws 16 or the like. The shafts 15 are of substantial thickness having a smooth, preferably polished, surface and are arranged in normal horizontal alignment being supported by blocks 14 and movable therewith. Rectangular pen supporting plates 17 are provided with spaced openings to slidably receive the guide shafts 15. Pens 18 of any suitable construction are bolted to the top edges of plates 17 and extend diagonally down to the belt 11, being held in proximity to the belt and the paper thereon by tension of springs 13. The plates 17 are provided with aligned central openings 19 and a screw shaft 20 is journaled in one of the blocks 14 extending freely through the aligned openings 19, and through the other block 14. The screw shaft 20 terminates in an operating crank 21 and is held in position between the blocks 14 by means of a collar 22 secured to the shaft and abutting against the inner edge of the block 14 as seen in Figures 2 and 3. The openings 19 are of greater diameter than screw shaft 20 and permit free rotation of the shaft. The end plate 17, adjacent collar 22, abuts against collars 23 secured to the guide shafts 15 at points spaced from the block 14 while the opposite end plate abuts against, or may be secured to, a cross-head plate 24 slidably engaging the guide shafts 15 and having a screw-threaded engagement with screw shaft 20. The pen holding plates 17 are maintained in even spaced relation by means of coil springs 25 of identical length and tension which surround shafts 15 between adjacent plates 17.

The spacing springs 25 will maintain an even spacing of the plates 17 and due to the spaced relation of guide shafts 15 which have a bearing contact with the openings in the plates 17 and the action of the springs 25 at opposite ends of pen holder plates 17, the plates 17 will be held in their parallel longitudinal position relative to the machine.

When it is desired to adjust the spacing of the pens 18, crank 21 is operated to rotate screw shaft 20 and move cross-head 24. The movement of the cross-head adjusts the position of

the adjacent plate 17 and as the opposite end plate 17 is held stationary by collars 23, the springs 25 will be compressed or expanded to move the intermediate plates 17 to provide a new even spacing of the plates and pens. By rotating crank 21 in the desired direction, the pens 18 may be moved farther apart or closer together under action of springs 25, always maintaining their even spacing and parallel relation. With this construction, only one set of pens is required for ruling lines of any desired spacing, and the desired adjustment may be easily and rapidly obtained.

In order to move the pens 18 out of contact with the paper to provide heading space or whenever it is desired to stop the ruling of the paper, I provide a lift finger 26 which may be clamped to the guide shaft 15 farthest from leaf spring 13 as shown in Figures 2 and 7, or secured in any other fashion to one of the blocks 14 or their connecting shafts. The finger 26 extends downwardly to a point adjacent the rail 10 and terminates in a normally horizontal extension through which an adjusting bolt 27 extends. A lock nut 28 engages the bolt 27 to maintain its adjusted position. A push rod 29 is slidably vertically in a sleeve 30 carried by the rail 10 of the machine and is arranged in vertical alignment with and directly below the adjusting bolt 27. The lower end of rod 29 extends below the sleeve 30 and carries a roller 31 which is adapted to engage the periphery of a rotating cam wheel 32 having a cam or cams 33 to engage the roller 31 and raise the push rod 29. The cam 33 is preferably removable so that cams of different sizes may be employed. The cam wheel 32 is rotated during

the operation of the machine by shaft 34 and when the cam engages roller 31 the rod 29 engages the lower end of adjusting bolt 27, thereby raising the blocks 14, shafts 15 and 20 and pens 18 against the tension of leaf springs 13, as indicated in Figure 7. While the pens are in their raised position, no lines are ruled on the paper, and as the roller leaves the cam 33 the pens are lowered into contact with the paper by springs 13.

While I have shown and described the preferred embodiment of my invention, it is to be understood that various changes in the size, shape and arrangement of parts may be resorted to without departing from the spirit of my invention or the scope of the subjoined claim.

Having thus described my invention, what I claim and desire to protect by Letters Patent is:

In a ruling machine, a pair of end members supported by the machine, a pair of spaced parallel guide shafts carried by the end members, a series of pen holders slidably supported on said guide shafts in spaced relation, a series of coil springs carried by each guide shaft and arranged between the pen holders to space the holders, said springs being of equal length and tension, stop members arranged adjacent one end of the shafts, adjusting means arranged between the guide shafts and engaging one of the pen holders to adjust the spacing of the pen holders, said adjusting means comprising a screw shaft rotatably supported by the end members and extending freely through openings in the pen holders, and means operatively connecting the screw shaft with the holder at the end of the series opposite to the stop members on the guide shafts.

LOUIS S. FORSYTHE.
